Albert S. Dietrich

ATTORNEY

UNITED STATES PATENT OFFICE.

EPHRAIM R. JONES, OF CORBIN, KENTUCKY.

EMBALMING ACCESSORY.

Application filed June 22, 1925. Serial No. 38,841.

To all whom it may concern:

Be it known that I, EPHRAIM R. JONES, a citizen of the United States, residing at Corbin, in the county of Whitley and State of Kentucky, have invented certain new and useful Improvements in Embalming Accessories, of which the following is a specification.

The invention generally relates to embalming accessories and has for its object to provide an improved construction of drain pan for use in facilitating the embalming function in a manner contributing considerably to the ease and efficiency of accomplishment thereof and insuring against undesirable soiling and destruction of carpets, rugs and the like by the spilling of fluid.

More specifically the present invention is an improvement on the apparatus disclosed in my application filed October 20, 1924, Serial No. 744,761, and it especially has for its object to provide a means which in case of purging from the mouth and nose the elevation of the body prevents blood and other ejecting fluid from flowing down under the back and creating unsanitary and unsightly conditions; I accomplish this object by providing the drain pan with a raised portion or elevation that is designed to fit close up against the body to the top of the shoulders in such a way that when the body is positioned on the board the elevated portion fits close and supports the back and extends to the top of the shoulders; in case of purging from mouth and nose, draining from jugular veins, excessive bleeding from wounds on head and face, washing and massaging, the liquids are all carried around the periphery of the elevated portions and prevented from flowing down under the back.

In the drawings:

Figure 1 is a perspective view showing the invention mounted for use.

Figure 2 is a central longitudinal section of the invention mounted for use.

Figure 3 is a side elevation of the invention.

Figure 4 is an enlarged detail section

taken substantially on the line 4—4 of Figure 2.

It is the common practice with embalmers, when operating on a body, to make an incision in the armpit, usually under the right arm and close to the body. The axillary vein is then raised and a drain tube inserted therein, a rubber tube being connected to the drain tube and to a blood bottle or other receptacle to take off and impound the blood.

Many difficulties arise in the carrying out of this procedure some of which are mentioned below and others of which will be obvious upon thought, and it is to provide an improved means, soon to be described in detail, for effectively overcoming such difficulties that I have addressed my efforts with signal success.

Often the blood will not flow as the arm pit incision is made and the drain tube and rubber tube operatively inserted. The natural course then is to disconnect the rubber tube. It is a common experience to have the blood start to flow copiously just when most inconvenient, just after the tube has been disconnected. If preliminary precautions have not been taken rugs and carpets are sure to be soiled or even ruined.

The embalmer's labor is commonly carried on in private homes and to guard against emergencies as above outlined it is necessary to spread rubber sheeting or similar means over the floor to protect against such accidental "spillings".

Also, it frequently happens, during the embalming operation, that a body purges, i. e. blood or blood mixed with other fluid flows excessively from the mouth and nostrils. This fluid naturally runs down over the face of the corpse onto the embalming board, and, if not properly restrained, onto the floor.

In addition to the above it is often necessary to wash and massage the face and shampoo the head. In cases of accident where the skin of the head and face is lacerated, excessive bleeding occurs and increases the difficulty of providing against "spillings".

In the present embodiment of my inven-

tion I provide a drain pan so constructed and adaptable to use as to be effective in receiving and confining the fluids exuding from the body and for providing for the proper carrying off of the fluids so confined. The device is removably mountable upon any approved type of embalming board, indicated in the drawing by the reference numeral 1, so as to be adaptable to use in the ordinary way (see Figure 1), i. e. as a head and shoulder support, or, as illustrated in Figure 3, it may be used beneath any portion of the body and on any part of the embalming board found desirable.

In general the device comprises an open frame composed of the side rails 2 and the cross or end rails 3. When used in the manner illustrated in Figure 1 the bottom cross rail 3 will be placed against any suitable edge or other abutment 4, so that when the lugs 5 with which the rails 2 are provided are properly engaged by the pivoted supporting arms 6, the device will be supported in the position shown for receiving the head, shoulders and upper portion of the body of the corpse.

To render my device universally adaptable it is made readily removable from the embalming table and the side rails 2 are provided with down-turned extensions 7 which serve to engage the embalming table for supporting the device in the manner illustrated in Figure 3.

35 By providing the open frame formed by the rails 2 and 3 the drain pan 9 is removably supportable on the frame.

The drain pan 9, which is preferably constructed of porcelain or enameled metal, has a turned down or cupped end portion 10 which not only provides a neat appearance, but fits down over the extended ends 7 and serves effectively to prevent longitudinal displacement of the pan, and inverted U-shaped side flanges 11 which snugly fit over the rails 2 to prevent lateral displacement of the pan.

50 The main body or drain portion of the pan is depressed between the flanges 11 from the portion which engages the upper rail 3 to the portion which engages the lower rail 3, the depressed portion being inclined so as to be about substantially flat at the upper end and about $1\frac{1}{4}$ " deep at the lower end. (See Figures 1 and 2.)

55 The lower end of the pan body terminates in an upwardly projecting back engaging roll 12 adapted to engage the back of the corpse to prevent overflow or the trickling of fluid down the back beyond the place where the roll 12 engages the same.

60 8 designates an elevated portion of the pan, the upper portion of which is of a curved outline somewhat of the nature of an inverted U and is designed to fit close up

against the back to the top of the shoulders and has for its purpose to prevent blood and other ejecting fluids from flowing down under the back and creating unsanitary and unsightly conditions.

70 The inclined pan bottom is adapted to effect drainage of fluid received thereon into the cross trough 13, the raised portion 8 serving to deflect the fluid around its periphery instead of letting it flow down along the back surface of the corpse. At one end of the trough 13, in one of the sides of the pan, a discharge aperture 14 which communicates with the off-take drain tube 15 is connected thereto at 16 as clearly indicated in Figure 4 of the drawing. The trough may be inclined if desired.

75 When, in effecting embalming operation, the body is positioned on my improved drain pan as described, all water used in washing, massaging and shampooing; all blood and other fluid exuding from the nose and mouth, is received and temporarily confined in the pan to be delivered through the tube 15 to the blood bottle or other receptacle 80 without any attention from the embalmer or danger of inadvertent spilling.

85 In the usual operation the body is positioned so that the arm pit is over the pan with the back between the shoulders resting 95 on the raised portion 8. All that is then necessary is to raise the vein and open it. The blood will flow onto the drain pan, into the trough 13 and out through the outlet 14; without special attention by the embalmer; without the necessity of using drain tubes, rubber tube connections, arm pit drain pans, rubber floor sheeting or a host of other nuisances an embalmer commonly has to tolerate. The drain pan is thus very effective, practical and desirable; also neat of appearance, sanitary, and very convenient of use.

90 When an abdominal incision is necessary, as in cases of dropsy and leakage into that cavity, I place the device under the body at that point and make the incision as low down on the side as possible. The same manner of use is employed in cases of other body incisions. In this manner the device is 100 universally effective.

105 From the foregoing description, taken in connection with the accompanying drawing, it is thought the novel details of construction, manner of operation and advantages, 110 will be readily apparent to those skilled in the art to which it relates.

115 What I claim is:

120 1. A device of the class described comprising a frame, a drain pan removably mounted on the frame, said drain pan having flanges to fit the frame, an inclined and depressed drain body portion, a cross trough portion into which the drain body portion 125 delivers, the said pan having a drain aper- 130

ture at one end of said trough, said inclined and depressed drain body portion having a raised portion to support the back of the corpse and fit close to the back extending to 5 the top of the shoulders thereof.

2. In a device of the class described, a drain pan having a rim portion and an inclined and depressed drain body portion, a

cross trough portion into which the drain body portion delivers, said pan having a drain aperture at one end of said trough and said pan having a raised inverted U shaped area above the trough to fit the back of the corpse and extend to the top of the shoulders thereof for the purposes specified. 10

EPHRAIM R. JONES.
